Attorney

UNITED STATES PATENT OFFICE.

FRANK B. STEPHENSON, OF DENVER, COLORADO.

SMOKING PIPE AND THE LIKE.

1,413,298.

Specification of Letters Patent. Patented Apr. 18, 1922.

Application filed June 19, 1920. Serial No. 390,104.

To all whom it may concern:

Be it known that I, FRANK B. STEPHENSON, a citizen of the United States, residing at Denver, in the county of Denver and State of Colorado, have invented certain new and useful Improvements in Smoking Pipes and the like; and I do hereby declare the following to be a full, clear, and exact description of the invention, such as will enable others skilled in the art to which it appertains to make and use the same.

This invention relates to new and useful improvements in pipes, cigar holders and similar smoking implements.

15 The main object of the invention is to afford a device of this character which shall have a long smoke channel or passage but a short stem and which is of a simple, efficient and easily cleaned construction.

20 A further object is to provide means to separate the smoke from saliva and condensation products so that the latter are retained in suitable receptacles and only the dry, clean smoke will be drawn into the 25 smoker's mouth.

Further objects will be more particularly indicated in connection with the details of construction.

The invention consists of an improved 30 compound stem and in the particular construction and arrangement of parts herein-after more fully described and specified.

One sheet of drawings accompanies this specification as part thereof, in which like 35 reference characters denote like parts throughout.

Referring to the drawings, Figure 1 is a vertical medial sectional view of the invention as applied to a pipe,

40 Figure 2 is a perspective view of a modified form of the device as applied to a pipe, the parts thereof being shown disconnected,

Figure 3 is an enlarged perspective view of the central part of the device,

45 Figure 4 is an elevation of the central section and joints in a modification of form of construction shown in Fig 1.

Figures 5 and 8 are transverse sectional view taken in opposite directions on the 50 line A—A of Figure 1, and

Figures 6 and 7 are transverse sectional views taken in opposite directions on a line B—B of Figure 1.

Referring to the drawings, the device consists essentially of three parts, an end section *a*, an intermediate section *b* and a stem

section *c*. The end sections are provided with the ordinary smoke ducts *i* and have their ends reduced to accommodate the collars *h*. The intermediate section *b* is provided with a plurality of parallel smoke ducts *f* and its ends are also reduced to accommodate the collars *h*. In the form shown in Figure 1, the intermediate part *b* is further provided on its ends with transverse tenons *d* and the ends of the stem section *c* and the end section *a* are preferably provided with mortises *d'* adapted to receive such tenons *d*. In the form shown in Figure 2, reduced ends *g* of the central section *b* are provided with mortises *e* and corresponding tenons *e'* are located within the collars *h* where mortises *d'* are not provided other means are used to prevent relative rotation of parts as shown in Figure 4 where the collars *h* may be provided with mortises *r* to receive projecting portions *s* from the central section.

The tenons *d* or *e'* are so proportioned that when the parts are assembled, chambers *o* will be left at each end of the intermediate part *b* in which saliva and the products of condensation will collect and be eliminated from the stream of smoke.

The end portions *a* may be made integral 85 with the bowl of a pipe *m* or may be provided with an extension *p* adapted to fit in any bowl *n*. Obviously, cigar or cigarette holders may be substituted for the pipe bowl.

90 By lengthening the intermediate part *b*, stems involving this invention can be made of any desired length to cool the smoke and the smoke ducts *f*, being straight, can be readily cleaned. By means of the mortise 95 and tenon construction shown the parts of the stem are secured against rotation and held in their proper relation to each other, preferably with at least one smoke duct in an elevated position as shown in Figure 1. 100

One of the important features of this invention is the arrangement of the tenons or partitions *d* with relation to each other and with relation to the parallel ducts *f*. This arrangement is clearly illustrated in Figs. 105 1, 2, 3, 5 and 6, and the arrows thereon; from examination of which it will be seen that the two tenons or partitions separate the ducts *f* in a different manner at the two ends of the central section. To illustrate, 110 suppose the three ducts designated as *f' f''* and *f'''*. The partition at one end will sepa-

rate f' and f'' from f''' while the partition at the other end will separate f' from f'' and f''' . The respective chambers o form connections between the ends of those ducts 5 respectively terminating therein. The result is that the smoke passes from the bowl section into and through one of the ducts as f' to its upper end, thence through chamber o into and through duct f'' to its lower 10 end, thence through chamber o into duct f''' to its upper end and into the duct in the mouthpiece. Thus the smoke, in passing from bowl section to mouthpiece, travels a distance equal to that of a stem three times 15 as long as the central section.

In previous inventions the smoke has been made to travel three times the length of the stem but the means whereby this was accomplished were difficult of construction and 20 cleaning as compared to my construction, and were less efficient and no saliva retaining means were provided in the construction.

What I claim is:

1. In a pipe stem having two end parts 25 each with a single smoke duct and an intermediate part with a plurality of smoke ducts, said parts secured in spaced longitudinal alignment to form chambers at each end of the intermediate part, transverse wall 30 members between said parts dividing said chambers in such manner as to form one continuous smoke duct through the stem.

2. In a pipe stem having two end parts, 35 each with a single smoke duct and an intermediate part with a plurality of smoke ducts, said parts secured in spaced longitudinal alignment to form chambers at each end of the intermediate part, mortise and tenon connections between said parts, said 40 tenons forming transverse wall members between said parts dividing said chambers in such manner as to form one continuous smoke duct through the stem.

In testimony whereof I affix my signature. 45
FRANK B. STEPHENSON.
